PARKING COIN DEPOSITORY

Henry Purl Compton, Abilene, Tex., assignor to
The Simplex Company, Abilene, Tex.

Application April 20, 1950, Serial No. 157,156

1 Claim. (Cl. 232—1)

1

This invention relates to parking meter.

An object of this invention is to provide a parking meter wherein a coin which is initially deposited will not be exposed until an authorized person inserts a key into the device and turns the key in one direction. Upon return of the key to its original position, release and dropping of the coin into the receiver will be effected.

Another object of this invention is to provide a parking meter which is so constructed and arranged that in the event the depositor of the initial coin unparks his vehicle before the end of the time period and a second vehicle enters the space, a second or any additional coin will bypass the first and not yet released coin and drop into the receiver. In this manner there will not be any jamming of the mechanism caused by deposits of additional coins before the first one has been released.

A further object of this invention is to provide a parking meter which is of very simple construction so that it can be produced at relatively low cost and will not readily get out of order.

With the above and other objects in view, my invention consists in the arrangement, combination and details of construction disclosed in the drawings and specification, and then more particularly pointed out in the appended claim.

In the drawings:

Figure 1 is a detailed front elevation of a parking meter constructed according to an embodiment of this invention.

Figure 2 is a vertical section taken substantially on the line 2—2 of Figure 3.

Figure 3 is a sectional view taken on the line 3—3 of Figure 2.

Figure 4 is a fragmentary elevation partly in section similar to Figure 2, but showing the coin release member in coin exposing position.

Figure 5 is a sectional view taken on the line 5—5 of Figure 4.

Figure 6 is a fragmentary sectional view taken on the line 6—6 of Figure 2.

Figure 7 is a fragmentary sectional view taken on the line 7—7 of Figure 2.

Referring to the drawings, the numeral 10 designates generally an upright housing which is formed with a cylindrical base 11 adapted to be secured by fastening means 13 to a supporting post 12. The housing 10 includes a rear wall 14 and upwardly divergent side walls 15 which merge into an arcuate top wall 16.

A closure generally designated as 17 is hingedly secured as at 18a to the upper portion of the cylindrical base 11 and comprises a front wall 18 formed with right angularly disposed and upwardly divergent side walls 19 having offset flanges 20 adapted to telescope over the sides 15 and the top wall 16. The top wall 16 is formed with a keeper 21 within which a locking bolt 22

2

is adapted to engage, and the locking bolt 22 is secured to cylinder lock structure 23 of conventional construction. The cylinder lock structure 23 is secured to the front wall 18 of the closure 17.

The front wall 18 of the closure 17 is provided with a coin slot 24, and the wall 18 is outwardly offset as at 25 above the slot 24 so as to prevent water from entering the slot 24. A plate 26 is pivotally mounted on a pivot 27 carried by the inner side of the front wall 18, and the plate 26 is disposed at its upper portion in confronting relation to the coin slot 24 and extends downwardly therefrom. The plate 26 is provided at a point below the coin slot with an outwardly extending lug 28 which forms a holder to initially support a coin 29.

The front wall 18 on the inner side thereof is also provided with a projection 30 having a downwardly and inwardly inclined edge 31 which forms a guide for the coin when the latter is released by inward rocking of the plate 26. The front wall 18 is formed with a window 32 at a point laterally from the guide 30 for exposing a coin which is released from the holder or lug 28. A lower lug 33 is carried by the plate 26 adjacent the lower end thereof and below the guide 30. The lug 33 is adapted to support the coin 29 when the latter is in confronting position to the window 32 as shown in Figure 4.

The plate 26 is formed with a laterally offset arm 34, and a lug 35 projects from the terminal end portion of the arm 34. A second lug 36 projects from the plate 26, and a plate locking bolt 37 engages between the two lugs 35 and 36. The bolt 37 is secured to a cylinder lock structure 38 which is carried by the front wall 18 of the closure 17. A V-shaped spring 39 bears against the inner side of the plate 26, and the apex portion of the spring 39 engages in a V-shaped flange 40 which projects from the closure 17.

The inner side of the closure 17 is formed with a rib 42 extending downwardly and inwardly from coin slot 24 so as to form a chute 43 with the adjacent wall 19 of closure 17. The chute 43 is wider than the diameter of a coin so that when the initial coin is held in the dotted position shown in Figure 2 by lug 28, a second or succeeding coin will upon striking the first coin roll inwardly and laterally by-passing the first coin and dropping into the receiver 11.

A screw 41 secures the apex of the spring 39 within the V-shaped flange or keeper 40.

In the use and operation of this device, when a single coin is initially inserted through the slot 24, this coin drops down between the plate 26 and the inner side of the closure wall 18. The coin 29 will engage the lug 28 which latter will hold the coin in a position above the window 32. At stated periods an authorized person will insert

a key in the lock 38 turning the bolt 37 so as to swing the plate 26. When the plate 26 is swung to the left as viewed in Figure 2, coin 29 will drop downwardly rolling along inclined edge 31 of guide 30 and striking the lug 33.

The coin 29 will at this time be exposed through the window 32. In order to remove the key from the lock 38, bolt 37 must be returned to its normal upright position shown in full lines in Figure 2, and at this time plate 26 is swung to the right so that coin 29 may drop downwardly into a collector which may be formed in the base 11 or at a point therebelow.

Assuming that an initial coin 29 is disposed in the meter and the vehicle is removed from the parking area before the end of the parking period when a second coin is inserted through the slot 24, this second coin will strike the first coin 29 which is held by lug 28 in the non-exposed position. The second coin will thereupon bypass the lug 28 passing downwardly to the left of this lug and then dropping down past the inoperative lug 33 into the receiver.

When the bolt 37 is turned at the end of the parking period, the initial coin 29 will become exposed through the window 32 so that the officer or authorized person will know that a proper coin has been deposited for use of the parking space.

With a meter as hereinbefore described where a number of vehicles enter a parking space within a single parking time or period, the succeeding coins which are inserted into the meter will all bypass the first deposited coin.

What is claimed is:

In a parking meter having an upright housing formed with a hollow base, and a closure hinged to said housing and formed with a coin slot with a coin guiding and releasing plate pivotally car-

ried by the inner side of said closure and extending downwardly therefrom; means for stacking a plurality of coins and releasing said coins individually, comprising a coin supporting lug carried by said plate below said slot adapted in the normal position of said plate to cooperate with an adjacent portion of said closure in holding an initial coin against dropping into said base, an inner downwardly extending rib carried by said closure forming a by-pass chute, a downwardly and inwardly inclined guide fixed to said closure below said lug and adapted upon engagement of a released coin to effect inward movement thereof, said closure having a coin exposing window adjacent said guide, a second lug carried by the lower portion of said plate adapted upon inward rocking of said plate to support a coin released from said first lug in confronting position to said window, outward rocking of said plate to normal position effecting release of the coin engaged with said second lug whereby the coin will drop into said base, said first lug being so positioned that when a coin is engaged therewith and a second coin is inserted in said slot, said second coin will strike said first coin and roll inwardly and downwardly to thereby bypass both of said lugs and drop into said base, and key actuated means for rocking said plate.
